(57) **CLAIM**

The ornamental design for an illuminated toilet seat, as shown and described.

DESCRIPTION

FIG. 1 is a front elevation view of the first embodiment of an illuminated toilet seat showing my new design showing a glowing filament in a transparent seat;
FIG. 2 is a rear elevation view thereof;
FIG. 3 is a side elevation view thereof;
FIG. 4 is a top plan view thereof;
FIG. 5 is a bottom plan view thereof;
FIG. 6 is a front elevation view of the second embodiment of an illuminated toilet seat, the difference being a battery-powered illuminated light filament;
FIG. 7 is a rear elevation view thereof;
FIG. 8 is a side elevation view thereof;
FIG. 9 is a top plan view thereof; and,
FIG. 10 is a bottom plan view thereof.
